UNITED STATES PATENT OFFICE.

DAVID M. DEARING, OF JACKSON, MICHIGAN.

RUNNING-GEAR FOR MOTOR-VEHICLES.

1,005,171.

Specification of Letters Patent. Patented Oct. 10, 1911.

Application filed November 12, 1909. Serial No. 527,624.

To all whom it may concern:

Be it known that I, DAVID M. DEARING, a citizen of the United States, residing at Jackson, in the county of Jackson and State 5 of Michigan, have invented certain new and useful Improvements in Running-Gear for Motor-Vehicles; and I do declare the following to be a full, clear, and exact description of the invention, such as will enable others 10 skilled in the art to which it appertains to make and use the same.

This invention relates to improvements in running gear for motor vehicles.

The object of the invention is to provide 15 a pivotal yielding connection between the front end of the supporting frame and the front axle and means whereby the weight of the frame and body of the vehicle is applied to the axle near the ends of the same.

20 With the foregoing and other objects in view, the invention consists of certain novel features of construction, combination and arrangement of parts, as will be more fully described and particularly pointed out in 25 the appended claims.

In the accompanying drawings, Figure 1 is a plan view of the front end of the motor vehicle running gear constructed in accordance with the invention; Fig. 2 is a front 30 end view of the same, parts being broken away and in section; Fig. 3 is a central vertical longitudinal sectional view; Fig. 4 is a plan view of the front end of the running gear showing a modified form of the invention adapted for use with elliptical side 35 springs; Fig. 5 is a side view of the same on the line 5—5 of Fig. 4; Fig. 6 is a front view of the upper and lower members of the connection, parts being broken away and in section; Fig. 7 is a central vertical longitudinal 40 section of the same on the line 7—7 of Fig. 6.

Referring more particularly to the drawing, 1 denotes the side bars of the supporting frame of the running gear, the forward ends 45 of which are connected together by a front cross bar or plate 2. To the lower side of the cross bar or plate 2 is bolted or otherwise secured the upper member 3 of my improved front axle connection. The member 50 2 is preferably in the form of a bar having on its opposite edges downwardly extending parallel flanges 4 which are increased in width at the center of the bar to form a bearing 5 as shown.

55 In the bearing portion 5 of the flanges 4 are formed alined bearing apertures 6. Adapted to be engaged with the upper mem-

ber 3 of the connection is the lower spring engaging member 7, said member preferably consisting of an angular bar provided at its center with a solid bearing portion 8 which is adapted to be inserted between the bearing portions 5 of the flanges 4 of the upper member 3. In the central bearing portion 8 of the lower connecting member is formed a bearing aperture which, when the parts are assembled, alines with the bearing aperture 6 in the flanges of the upper member and through said alined passages or apertures is inserted a tubular bearing sleeve 9, 70 by means of which the upper and lower members of the connection are pivotally connected together. The bearing sleeve receives the cranking shaft 10 which is mounted therein and is provided on its outer end with 75 the usual crank handle 11. The lower member 7 tapers or inclines from the center of the member toward the ends thereof and the ends are bent upwardly to form brackets 12, on the upper ends of which are formed vertically disposed sockets 13 with which are adapted to be engaged the upper ends of guide pins 14, the lower ends of which are secured to the front axle 15 adjacent to its outer ends by means of clips 16, or other 80 suitable fastening devices.

On the pins 14 between the enlarged lower ends of the sockets 13 and the clips 16 are arranged coiled supporting springs 17, which receive and yieldingly support the weight 90 of the running gear and body of the vehicle. By arranging the springs 17 near the outer ends of the axle 15, the weight of the vehicle body and running gear is imparted to the axle near its engagement with the supporting wheels thereby relieving the central portion of the axle from such weight, and thus reducing the possibility of bending or breaking the axle. The pivotal engagement of the lower connecting member with the upper member permits the outer ends of the axle to rock or move up and down, thus relieving the running gear and operating parts 95 of the vehicle from undue strain.

On the lower side of the upper connecting 105 member 3 adjacent to its outer ends are arranged upper bumpers 18, while on the upper sides of the lower member 7 are arranged lower bumpers 19. The bumpers 18 and 19 are provided to limit the rocking movement of the axle, and by forming the bumpers of greater or less length, the rocking movement of the axle may be regulated. Between the outer ends of the upper and

lower connecting members and around said bumpers are preferably arranged coiled cushioning or shock absorbing springs 20, by means of which jars or shocks occasioned by the vehicle passing over rough or uneven surfaces are taken up. The axle 15 is connected with the side bars of the supporting frame by brace rods 21 which are connected at their front ends by universal joints 22 with the clips 16 and at their rear ends by universal joints 23 with the side bars in the common well-known manner to permit the necessary movement of the parts.

In Figs. 4-7 of the drawings is shown a modified arrangement of the connecting members, whereby they are adapted for use in connection with elliptical side springs instead of coiled springs as shown in the first figures of the drawing. The connection 20 shown in the last figures of the drawings comprises an upper frame engaging bar 24 having on its opposite side edges downwardly projecting flanges 25 in the center of which are formed alined bearing apertures 26. The lower connecting member 27 is secured in a similar manner to the member 7 of the first form of the device and is adapted to be inserted between the flanges 25 of the upper member and in the center of said lower member is formed a bearing aperture 28 which, when the parts are assembled, alines with the bearing apertures 26 and through said alined apertures is inserted a tubular bearing sleeve 29, through which the cranking shaft 10 is inserted. On the upper side of the member 27 on the opposite sides of and near the center are formed stop lugs 30 immediately above which on the inner side of the upper member 25 are arranged bumpers 31, which are adapted to engage the lugs 30 and thereby limit the rocking movement of the lower member 27. If desired, coiled springs 32 may be arranged between the bumpers 31 and the lugs 30. On the outer ends of the member 27 are formed brackets or hangers 33 having right angular outwardly projecting hook-shaped ends 34, which are adapted to be engaged with the upper sides of elliptical side springs 35, which are secured at their lower sides to the front axle 15 adjacent to its opposite ends as shown. With this form of the connection may be used any kind of elliptical, bowed or leaf springs to yieldingly support 55 the frame and body of the vehicle.

From the arrangement shown in the drawings, it will be seen that the bumpers and the bumper springs may be placed at any desired position between the center and outer 60 ends of the connecting members. It will also be understood that in the last form of the invention, the brace rods 21 are connected to the axle and frame in the same manner as

described in connection with the first form of the invention.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of this invention as defined in the appended claims.

Having thus described my invention, what I claim is:

1. In a motor vehicle running gear, the combination of a supporting frame, a front axle, an upper connecting member on the under side of the frame, a lower connecting member having its central portion housed within said upper connecting member and its ends arranged over the ends of the axle, a sleeve inserted through the central portions of said members, to pivotally connect the same, cushioning devices arranged between said members at opposite sides of said sleeve, and springs arranged between the ends of the lower connecting member and the axle.

2. In a motor vehicle running gear, the combination of a supporting frame, a front axle, an upper connecting member on the under side of the frame, a lower connecting member having its center housed within the upper member and its ends arranged over the ends of the axle, a sleeve inserted through the centers of said members to pivotally connect the same, springs arranged between the ends of the lower member and the axle, bumpers arranged between the upper and lower connecting members, and springs arranged on said bumpers.

3. In a motor vehicle running gear, the combination of a frame, a front axle, an upper connecting member on the under side of the frame having depending flanges, a lower connecting member fitted between said flanges and having its ends disposed over the ends of the axle, a sleeve inserted transversely through the center of the lower connecting member and the flanges of the upper connecting member to pivotally connect said members and form a bearing for the cranking shaft, cushioning devices between the members, and springs on the axle engaging the ends of the lower connecting member.

In testimony whereof I have hereunto set my hand in presence of two subscribing witnesses.

DAVID M. DEARING.
